WASHING MACHINE

Henry C. A. Meyer, Syracuse, N. Y., assignor to
 United States Hoffman Machinery Corporation,
 New York, N. Y., a corporation of Delaware

Application May 9, 1942, Serial No. 442,314

1 Claim. (Cl. 68—58)

1 This invention relates to washing machines, and more particularly to machines wherein clothes may be washed thoroughly and then be quickly and economically rinsed without removing them from the washer or disturbing the operation of the machine.

In its present embodiment the invention is shown as comprising a single cylindrical container of the tubless or shell-less type into which washing fluids may be admitted through a supporting trunnion disposed at one end of the cylinder and clothes to be washed be admitted to the cylinder through a charging door arranged substantially in coaxial alignment with the cylinder and its trunnion.

One object of the invention is to provide improved means for effecting continuous rinsing of the clothes at the end of a processing operation, not only by the usual process of dilution of the washing solutions contained therein by the addition of rinse water, but by actually forcing the discharge of such solutions from the cylinder at the end thereof opposite the points of admission of rinse water.

Another object of the invention is to provide conduits arranged peripherally within the wash cylinder adapted to lead rinse water from a supply means into the cylinder predominantly adjacent one end thereof and to receive and discharge liquids from the cylinder predominantly adjacent the opposite end thereof.

A further object of the invention is to provide means for facilitating the discharge of solutions from the washer and controlling the rate of such discharge by the employment of a discharge or dump valve especially adapted to attain that result.

Other objects will be in part obvious or in part pointed out hereinafter.

The invention accordingly consists in the features of construction, combinations of elements and arrangements of parts as will be exemplified in the structure to be hereinafter described, and the scope of the application of which will be indicated in the following claim.

In the accompanying drawings, in which is shown one of the various possible embodiments of the mechanical features of this invention;

Fig. 1 is a front elevation;

Fig. 2 is a longitudinal section taken along the line 2—2 of Fig. 1 showing parts in elevation;

Fig. 3 is a transverse section taken along the line 3—3 of Fig. 2;

Fig. 4 is an enlarged section through the dump

2 chamber and valve taken along the line 4—4 of Fig. 5; and

Fig. 5 is an enlarged section taken along the line 5—5 of Figs. 2 and 4.

Similar reference characters refer to similar parts throughout the various views of the drawings.

Referring to the drawings, a washer embodying certain features of my invention will be seen to consist of a rotatable imperforate cylindrical shell or drum 10 having at its front end a flanged annular disc or head 12 and at its rear end two spaced heads 14 and 16. The space between the heads 12 and 14 constitutes a processing chamber 11 while the narrower space, between the heads 14 and 16, provides a mixing chamber 15 to initially receive water, steam and laundry supplies and, after mixing, to deliver the same to and through the tumbling ribs 18 to the processing chamber 11 of the cylinder. The tumbling ribs 18 serve not only as induction conduits but also for the purpose of educting or draining washing fluids from the washer in a particular manner, as will appear hereinafter.

25 The head 16 of the cylinder is secured by means of flanges 17 to a rugged gear frame 20 provided with gear teeth 21 which mesh with the similar teeth of a drive pinion 22. This pinion is rigidly mounted upon a shaft 23 carrying rigidly a sprocket 24 rotatably connected by means of a driving chain 25 with a sprocket 26 mounted upon the shaft of a reversible driving motor 27.

The circular gear frame 20 is rigidly mounted upon a trunnion member 28 which extends into and is supported by adequately spaced bearings (not shown) supported within a housing member 30, itself fastened to a frame pedestal member 32. Any suitable bearing structure adequate to support the weight of the washer cylinder solely at one end in cantilever fashion and to permit rotation of said cylinder, may be employed.

An inlet pipe 33 extends through the trunnion member 28 coaxially with respect to the cylinder and trunnion and opens into the mixing chamber 15. At its outer end this inlet pipe connects suitably, as by means of the Venturi fitting 34, with a steam pipe 35, a hot and cold water supply conduit 36, a fluid recirculation pipe 37 and a pipe 38 which may connect with any suitable tank for supplying to the inlet pipe 33, as desired, laundry supplies such as alkali, soap, sour, blue, etc. It will be seen that suitable valves are included in these various pipe lines to control the function of each.

55 The bearing assembly, the motor and drive con-

nections for rotating the cylinder are all supported by means of the rigid frame member 32 mounted upon a base plate 1.

Water, steam and supplies are directed as desired through the supply pipe 33 into the mixing chamber 15 which connects with the processing chamber 11 of the cylinder solely by means of the washing or tumbling ribs 18. These ribs connect with the mixing chamber through large openings 40 whereby washing or processing fluids supplied are directed to the inlet space 41 of each rib. This space is formed by the apex and side walls of the rib and a plate 42 hermetically sealed within the rib; and from this space 41 materials are inducted into the processing chamber through perforations or holes 43, the spacing of which lengthwise the rib and the flow area of which lengthwise the rib, will be described later.

Water and supplies escape from the washer or processing chamber solely by means of holes 44 located in the lower sections 45 of the ribs 18 below the plates 42, the arrangement of which holes will be more fully described hereinafter. Discharge fluids then move forwardly within said ribs toward the front end of the washer and through suitable openings 46 provided in the head sheet 12 in alignment with the sections 45 of the ribs. Plates 47 joined in T formation with the plates 42 and secured to the cylinder shell prevent processing solutions from flowing directly through the rib during cylinder rotation.

A sheet metal housing 48 supported by the bed plate surrounds the cylinder above and on all four sides. A narrow space 50 is provided between the front cylinder head 12 and the front sheet 49 of the housing. This sheet is generally rectangular in shape and extends from the base plate upward to the top of the structure. The space 50 receives the discharge liquid from the discharge portions of the ribs and is connected by means of an opening 51 in the end sheet 49 with the interior of a casting 52 bolted to the front sheet, whence the solutions are conducted to a dump valve, generally indicated by the number 53, by means of a connecting conduit 54. The dump valve inlet space 55 is preferably connected with the Venturi fitting 34 by means of the pipe 37 whereby the processing liquids may be recirculated through the washer during cylinder operation. Thus during this recirculation the processing liquids may be made, by admitting steam to the fitting 34, to flow from within the wash cylinder to the space 50, then through the dump valve body and connecting piping back through pipe 33, mixing chamber 15 and back into the cylinder by means of the induction sections of the tumbling ribs 18.

To avoid escape of liquids from the washer and the space 50, a circular seal 56 is provided. This seal extends completely around the outer flange of the head sheet 12 and is held fast by means of a strap 57.

To provide for ready access to the inside of the wash cylinder there is provided a hinged door and door frame assembly, the centers of which coincide with the center line of the cylinder. The door frame 60 is rigidly fastened to the front sheet 49 of the washer housing and the door rim 61 is supported by hinged lugs 62 and 63 integral respectively with the frame and rim. The door comprises a heavy glass 64 which is sealed tightly to the door rim 61 by means of a rubber lute 66. The door is normally held tightly closed by means of a suitable latch 65.

Referring to Fig. 2 of the drawings, it will be

understood that the disclosed arrangement of perforations 43 in the upper portions of the ribs 18 is intended to indicate, either in respect to their specific location or to their flow areas, that induction occurs predominantly near the inlet end of the washer cylinder; and that the arrangement of the eduction holes 44 in the lower portions of the ribs is intended to indicate, either in respect to their specific location or flow areas, that eduction occurs predominantly near the discharge end of the cylinder. It has been found that this arrangement of inlet and outlet holes greatly facilitates the rinsing operation. Heretofore rinsing has been strictly a dilution process, the addition of fresh rinse water having been practically proportioned to the rate of discharge from the washer during the rinsing operation so as to effect dilution of the processing liquids within the wash cylinder at a more or less predetermined rate. With the present arrangement the rinse water coming into the processing chamber predominantly near one end of the cylinder will cause the wash solution to be discharged near the other end, thus resulting in a process of displacement as well as dilution. This combined action, as shown by test, is much faster than simple dilution and requires much less rinse water to attain similar rinsing results.

It will be understood that during a rinsing operation or at the end of a complete washing cycle it is necessary rapidly to carry the liquid away from the wash cylinder and discharge it to a suitable drain. To this end a dump valve is used which may be manually opened at any desired moment during cylinder operation or, in fact, when the cylinder has been brought to rest. Accordingly an important feature of the present construction is a dump valve particularly well adapted for rapid manual operation, of simple construction, and having the valuable characteristic that it may be quickly opened to any desired extent and automatically held at the degree of opening selected. Thus during rinsing it may be desirable to give slight opening to the discharge, while at the end of the washing operation a full opening would be wanted.

Referring to Figs. 2, 4 and 5, the present dump valve will be seen to comprise a main body 53 which is connected by means of a flange 70 to a flange 71 carried by the conduit 54 connecting with the interior of the casting 52. The valve body is provided with a flanged head 72 having a downwardly dropped flange 73 which fits closely within the receiving space 55 of the body. Below the lower end of this flange the walls of the body are internally flanged to provide a valve seat 74 surrounding a circular valve opening 75. Loosely mounted on this seat is an annular gasket 76, which may be installed or renewed through the upper open end of the valve body when the head 72 is removed. When the head 72 has been fastened down, in any suitable manner, the lower end of the flange 73 holds the gasket firmly in place.

The valve proper comprises a disc 77 adapted to bear upon the gasket 76 adjacent the opening 75 and having a downwardly extending stem 78 slidably mounted in a guide member 81 forming part of the valve body. Below the guide the valve stem is slotted to provide a seat for a circular cam 79, eccentrically mounted on a cam operating rod 80. The rod 80 extends horizontally through a bearing 81 formed in the valve body and another bearing 82 formed on the casting 52. At its outer end the rod is fitted with

a suitable operating handle 83 which may serve as an indicator in relation to a scale 86 calibrated to show various degrees of valve opening. By means of this circular cam the valve may readily be thrown from fully closed to fully open position or to any point therebetween, and because the cam itself serves as a position lock no other means is needed to hold the valve in its desired open position. As indicated at 84 and 85, the flange 73 of the valve body head is provided with suitable openings in registry with conduits 31 and 54. The lower end of the valve body is open to permit discharge of liquids through an opening in the base plate 1 to any suitable sewer or drain.

It will therefore be seen that the present invention is one well adapted to attain the objects hereinbefore set forth, and that it provides special features resulting in many other advantages in respect both to manufacture and operating efficiency.

As many possible embodiments may be made of the above invention without departing from the scope thereof, it is to be understood that all matter herein set forth or shown in the accompanying drawings is to be interpreted as illustrative and not in a limiting sense.

I claim:

In a shell-less washer having an imperforate

rotatable wash cylinder, in combination, means for admitting liquid to the interior of said cylinder comprising a plurality of inlet conduits extending lengthwise within said cylinder each adapted to receive liquid through an inlet opening connecting with a liquid receiving space at one end of the cylinder and having means communicating with the interior of the cylinder comprising a plurality of perforations distributed lengthwise the conduit the aggregate flow area of which is greatest adjacent the inlet end of the conduit and progressively less per unit of conduit length away from said inlet end, means for discharging liquids from said cylinder comprising a plurality of discharge conduits extending lengthwise within said cylinder each adapted to discharge liquid through an outlet opening connecting with a liquid discharge space at the other end of the cylinder and having means communicating with the interior of the cylinder comprising a plurality of perforations distributed lengthwise the conduit the aggregate flow area of which is greatest adjacent the discharge end of said conduit and progressively less per unit of conduit length away from said discharge end, and controllable means for supplying rinse liquid to said receiving space and controllable means for discharging liquids from said discharge space.

HENRY C. A. MEYER.
